UNITED STATES PATENT OFFICE.

WILLIAM WALLACE KEMP, OF BALTIMORE, MARYLAND, ASSIGNOR OF ONE-HALF TO
WILLIAM H. VAN HORN, OF BALTIMORE, MARYLAND.

METHOD OF AND APPARATUS FOR CASE HARDENING.

Application filed November 7, 1921. Serial No. 513,443.

To all whom it may concern:

Be it known that I, WILLIAM WALLACE KEMP, a citizen of the United States, residing at Baltimore, in the county of Baltimore 5 City and State of Maryland, have invented new and useful Improvements in Methods of and Apparatus for Case Hardening, of which the following is a specification.

The present invention relates to a method 10 of and apparatus for case hardening, and has for its object to provide for the treatment of articles by means of any suitable carbonizing agent at the same time that they are being subjected to the direct heating action 15 of a flame.

Various methods for case hardening have been heretofore proposed. Under one method there has been proposed placing articles to be hardened in a retort together with a 20 suitable carbonizing agent, and subjecting that retort to external heating to bring the articles to the proper temperature to take up the carbonizing medium. Another method has been to first heat the articles in a 25 proper container by direct heat until they are brought to the desired temperature, and then either removing them from the container and bringing them into the presence of the carbonizing agent, or to extinguish 30 the heating flame and then introduce the carbonizing material into the presence of the heated articles.

Both of these methods are objectionable 35 the first for the reason that where the articles and the carbonizing agent are placed in the retort and the retort is subjected to external heat, the retorts tend to break down from the excessive heat required to bring the interior of the retort to the proper temperature, and, furthermore, the operation of loading the retort with the articles to be hardened and introducing the hardening agents is cumbersome and expensive. The operation of directly heating the articles, 40 then removing them from the action of the heating agent into the presence of a carbonizing medium; or extinguishing the flame, and introducing the carbonizing agent, is slow and tedious.

50 A serious objection to both of the methods above set forth is that it is difficult to maintain the articles at a uniform heat, which is a very essential thing, in order that when

the articles have been brought to a proper temperature, they may be maintained at that 55 temperature during the action of the carbonizing agent.

My method and apparatus contemplate the internal firing of a retort and the heating of the articles contained therein in the 60 presence of the carbonizing agent, this being accomplished by the use of a self-sustaining fuel which will burn in the presence of the carbonizing agent without any 65 danger of ignition and burning of that carbonizing agent. Following my method and utilizing my apparatus, it is possible to maintain, in a closed retort, a heating flame or jet which will bring the articles to and maintain them at a proper and uniform 70 temperature for case hardening; and, at the same time, introduce into the retort the case hardening agent without any danger of smothering the heating flame or igniting the carbonizing element. 75

In order that the invention may be clear to those skilled in the art, I have shown, in the accompanying drawings, one physical embodiment of my invention, but it will be understood that this disclosure is merely 80 illustrative and in no sense restrictive of the invention, as apparatus other than that shown in the drawings, may, of course, be used in practicing my method.

In the drawings:—

Figure 1 is a view in side elevation of a retort by which my method may be practiced.

Figure 2 is a longitudinal section of the retort shown in Figure 1. 90

Referring to the drawings by numbers, like numbers indicating like parts in the several views, 10 indicates a retort of any suitable construction and design, it being here shown as a cylindrical metal container lined, if desired, with refractory material, conventionally shown. Said retort is provided with a door 11, which is so fashioned that it may be tightly closed so that the retort 10 will be substantially closed against the entrance of atmospheric air. Mounted within the retort 10 is a cage or rattler 12 which will be provided with a door 13 to provide a loading opening. The cage 12 has a foraminous wall, as shown, and is 100 preferably mounted for revolution on 105

gudgeons 14, passing through stuffing boxes 15 in the ends of the retort 10, suitable means (not shown) being provided for rotating the cage 12 which receives the articles 5 to be case hardened.

The retort 10 is provided at suitable points, preferably at one end, with one or more fuel pipes 16, four being shown in the present case, distributed circumferentially 10 approximately 90° apart and delivering, preferably, outside of the circumferential area of the cage 12, so that the cage and the articles contained therein will be substantially surrounded by the heating medium.

15 The said pipe or pipes 16 deliver a mixture of fuel, preferably gaseous, to the closed retort 10, this fuel being preferably a mixture of gas and air in such proportions that it will be self-sustaining and will burn in the 20 closed retort in the absence of air from any independent supply.

There will, of course, be no air to support combustion in the retort 10, for the fuel delivered from the pipes 16 has an air content 25 sufficient only to sustain combustion of the fuel, and not enough to permit ignition and burning of the carbonizing agent. Atmospheric air cannot enter the retort 10 in sufficient volume to support combustion, for 30 with the closed retort 10, there is no chance for ingress of air in any quantity, and the pressure within the retort will be such as to effectively overcome atmospheric pressure tending to force air into the retort.

35 This carbonizing agent, which may be either in granular, liquid, or gaseous form, may be introduced into the retort 10 in any suitable fashion, either when the retort is loaded, or, if desired, by providing any 40 feed pipe or opening delivering to the retort 10. Under this method, and with this arrangement, the articles to be case hardened may be simultaneously subjected to the heating and the carbonizing actions, so that they 45 may be brought to any desired temperature and there maintained during the carbonizing 50 process.

This method has the advantage over 55 methods known to me of permitting the articles to be brought to the desired temperature and maintaining them uniformly at that temperature until penetration and hardening has progressed to the point desired, so that immediately the absorption 60 temperature is reached, the case hardening begins and is continued without interruption, and there is no chance of variations in temperature of the articles during the treatment, which would result in imperfect

65 and non-uniform hardening.

It will be understood that the fuel delivered to the retort 10 from the pipes 16 is of such character that it will sustain combustion in the absence of air within the closed 70 retort, the air content of the mixture being

so proportioned as to accomplish this result, but that the carbonizing agent will not ignite for the reason that there is not, within the retort 10, which is substantially closed against the ingress of atmospheric air and 75 within which is maintained a sufficient pressure to exclude the entrance of air, sufficient oxygen to sustain combustion. The danger of burning the carbonizing mixture is, therefore, eliminated. 75

The retort 10 will preferably be provided with a bleeder 17 through which the waste gases will be forced by pressure within the retort, and these waste gases may be conducted away or burned at the orifice of 80 the bleeder 17, as may be desired.

Under this method and utilizing this apparatus, I have provided an economical and simple way of case hardening articles, eliminating the external firing method with the 85 closed retort, now commonly in use, or the somewhat cumbersome method of first firing and then subjecting the fired articles to the action of the carbonizing agent.

Such changes in the apparatus and new 90 steps of the method as are within the skill of the mechanic may be made without departing from the range of my invention.

I claim:

1. The method of case hardening, which 95 consists in enclosing the articles in a container and heating them by combustion within the container in the presence of a carbonizing agent without igniting the carbonizing agent. 100

2. The method of case hardening, which 105 consists in enclosing the articles in a container and heating them by a flame within the container in the presence of a carbonizing agent without igniting the carbonizing agent. 110

3. The method of case hardening, which 115 consists in enclosing the articles to be treated in a container, bringing the articles to a proper temperature by burning a self-sustaining fuel in said container, and subjecting the articles to the action of a carbonizing agent without igniting said carbonizing agent. 110

4. The method of case hardening, which 115 consists in enclosing the articles to be treated in a container, bringing the articles to a proper temperature by introducing a self-sustaining flame interiorly of said container, and simultaneously subjecting the 120 articles to the action of a carbonizing agent without igniting said carbonizing agent.

5. The method of case hardening, which 125 consists in enclosing the articles to be treated in a container, bringing the articles to a proper temperature by introducing a self-sustaining flame interiorly of said container, agitating the articles, and subjecting them to the action of a case hardening agent without igniting said carbonizing agent. 130

6. The method of case hardening, which consists in enclosing the articles to be treated and a suitable case hardening agent in a container, and bringing said articles to a proper temperature by introducing a self-sustaining flame into said container without igniting said carbonizing agent. 45
7. Apparatus for case hardening articles, comprising a container adapted to receive the articles and a carbonizing agent, and means for introducing a combustible fuel into said container and burning it therein without igniting the carbonizing agent. 50
8. Apparatus for case hardening articles, comprising a container adapted to receive the articles, a receptacle for the articles to be hardened in said container, and means for introducing a self-sustaining flame into said container without igniting the carbonizing agent. 55
9. Apparatus for case hardening articles, comprising a container adapted to receive the articles and a carbonizing agent, a receptacle for the articles to be hardened in said container, means for agitating the articles, and means for introducing a self-sustaining flame into said container without igniting said carbonizing agent. 60
10. Apparatus for case hardening articles, comprising a container adapted to receive the articles and a carbonizing agent, a foraminous receptacle for the articles to be hardened in said container, means for agitating the articles, and means for introducing a self-sustaining flame into said container without igniting said carbonizing agent. 65
11. Apparatus for case hardening articles, comprising a container adapted to receive the articles and a carbonizing agent, a movable receptacle for the articles to be hardened in said container, and means for introducing a self-sustaining flame into said container without igniting said carbonizing agent. 70
12. Apparatus for case hardening articles, comprising a container adapted to receive the articles and a carbonizing agent, a revolvable receptacle for the articles to be hardened in said container, and means for introducing a self-sustaining flame into said container without igniting said carbonizing agent. 75
13. Apparatus for case hardening articles, comprising a stationary container adapted to receive the articles and a carbonizing agent having bearings at each end thereof, a foraminous receptacle for the articles to be hardened revolvably mounted in said bearings, and a burner delivering a self-sustaining flame interiorly of said fixed air-tight container without igniting said carbonizing agent. 80
14. Apparatus for case hardening articles, comprising a stationary container adapted to receive the articles and a carbonizing agent and having bearings at each end thereof, a foraminous receptacle revolvably mounted in said bearings, and a plurality of burners delivering self-sustaining flames about said foraminous receptacle without igniting said carbonizing agent. 85
15. Apparatus for case hardening articles, comprising a stationary container adapted to receive the articles and a carbonizing agent and having bearings at each end thereof, a foraminous receptacle revolvably mounted in said bearings, a plurality of burners delivering self-sustaining flames about said foraminous receptacle without igniting said carbonizing agent, and a bleeder pipe delivering from said container. 90

In testimony whereof I have hereunto set my hand.

WILLIAM WALLACE KEMP.
